25/11 # UNITED STATES PATENT OFFICE.

DESIRE H. VAN HOVE, OF JACKSON, MICHIGAN, ASSIGNOR TO REYNOLDS SPRING COMPANY, OF JACKSON, MICHIGAN.

SPRING STRUCTURE.

1,387,743.

Specification of Letters Patent. Patented Aug. 16, 1921.

Application filed January 27, 1921. Serial No. 440,450.

To all whom it may concern:

Be it known that I, DESIRE H. VAN HOVE, a citizen of the United States, residing at Jackson, in the county of Jackson and State 5 of Michigan, have invented new and useful Improvements in Spring Structures, of which the following is a specification.

This invention relates to spring structures.

- 10 One object of the invention is to provide a spring structure for automobile or other seats, embodying among other characteristics, an edge for the structure designed to prevent sagging or swaying of the structure and affording a stiff spring structure 15 for the support of the upholstery, and yet providing a structure capable of taking care of the varying weights without danger of a complete compression of the springs, thereby 20 providing for a soft and easy riding for the occupant of the seat.

Another object of the invention resides in the provision of a spring structure embodying upper and lower frames connected together by relatively stiff border springs within which is disposed a group of springs forming a center double-deck arrangement of springs surrounded by an intermediate frame in combination with the top truss or 30 stay wires connected to the upper frame and to said intermediate frame, the adjacent truss or stay wires being arranged preferably in opposite direction with relation to each other.

35 With the above and other objects in view, the present invention consists in the combination and arrangement of parts hereinafter more fully described, illustrated in the accompanying drawing and particularly 40 pointed out in the appended claims, it being understood that such changes in the size, form, proportions and minor details as will be permitted under the appended claims may be resorted to without departing from the 45 spirit of the invention or sacrificing any of the advantages thereof.

In the drawings:

Figure 1 is a top plan view of the invention.

50 Fig. 2 is an end elevation.

Fig. 3 is an enlarged detail cross-sectional view on the line 3—3 of Fig. 1.

Fig. 4 is a detail perspective view of one of the clips employed in the structure.

55 Fig. 5 is a fragmentary perspective view

illustrating the manner of connecting one of the truss or stay wires to the upper border frame.

Referring now more particularly to the accompanying drawings the reference character 6 indicates an upper border frame of wire or any other suitable material and 7 indicates a channeled or other suitable lower border frame, in this instance, having a wood insert 8 to which the lower edges of the facings of the upholstering material (not shown) may be secured, and also having a longitudinal groove 9 designed to receive and secure the lower convolutions of the border springs which latter are also supported upon the supporting bars 10 of channeled or other suitable formation. These border springs may be connected to the upper and lower border frames and to their supporting means in any suitable manner, 65 70 75 suitable clips 11 being used to secure them to the upper border frame. These border springs are preferably of the double cone type, as shown.

The character 12 indicates pairs of spring 80 supporting bars and which are preferably of channeled shape and in the channels of which are secured in any suitable manner rows of springs 13, 14 and 15 which constitute the lower portion of a group of springs 85 forming a center double-deck structure A. These springs are of the double cone type, and are relatively short, compared with the border springs, being of a height substantially one-half of the height of the border 90 springs; and of a gage of material of substantially the same gage as that of the border springs.

An intermediate wire or other frame 16 is mounted upon and surrounds the springs 13, 95 14 and 15 at the upper ends of the latter. A wire netting or other suitable material 17 is stretched tightly across this intermediate frame 16 and is secured thereto by means of suitable clips 18, to deaden sound between 100 the springs.

A set of springs arranged in rows 19, 20 and 21 constitute the upper portion of the aforesaid center double-deck structure A and they are arranged upon the rows of springs 105 13, 14 and 15, respectively. These springs 19, 20 and 21 are of the double cone type but of lighter gage wire than the lower set of springs 13, 14 and 15, there being one of these lighter springs arranged directly over 110

each of the interior springs 13, 14 and 15 but separated therefrom by said wire netting 17. These upper and lower sets of springs are connected together at their abutting ends 5 and to the said intermediate frame by means of suitable clips 22, with the bases of all of said upper set of springs connected together by means of suitable clips 23, said clips 23 being arranged above the netting 16. 17. The innermost springs of the lower set of interior springs are connected together at their upper ends beneath the netting 17 by means of suitable clips 24. Clips 25 connect the said intermediate frame 16 with the 15 border springs, as shown, and clips 26 preferably connect the upper convolutions of the set of interior springs together and to the border springs, as shown.

Truss or stay wires 27 and 28 are employed, the stay wire 27 having its outer end 29 directed laterally and secured to the upper frame by means of a suitable clip 30 and having its opposite end laterally directed, as at 31, and secured to the farther 25 side of the intermediate frame 16 by means of a suitable clip 32. The stay wire 28 is of the same formation as the stay wire 27 and it is secured to the upper border frame and to the intermediate frame in the same manner, but, as will be noted, the stay wire 28 extends in a direction opposite to the direction of the stay wire 27, such arrangement of the stay wires holding the entire structure against side thrusts and yet not affecting 35 the resiliency of the structure.

If desired, there may be employed a supporting wire 33 which may extend longitudinally across the bottom of the structure and have its ends secured to the lower frame 40 and to which some of the springs may have their lower ends connected, but whether the springs be connected to this stay wire 33, the latter serves as a brace to strengthen the base of the structure.

45 What is claimed is:

1. In a spring structure, a frame, border springs connected to the frame, a group of upper and lower springs arranged within the border springs, the upper springs of 50 said group being of lighter gage wire than the lower set of springs and of lighter gage wire than the border springs, a frame arranged within said border springs and connected to said group of springs, a wire netting 55 stretched across the last mentioned frame and secured thereto and arranged between the upper and lower sets of springs of said group of springs, and connections between said second mentioned frame and certain of the border springs.

2. In a spring structure, an upper frame, a lower frame, border springs arranged between the upper and lower frames, a group of upper and lower springs arranged between the upper and lower frames and with-

in said border springs, a frame arranged between the upper and lower frames and within the border springs and connected to said group of springs, a wire netting stretched across the intermediate frame and 70 secured thereto and arranged between the upper and lower sets of springs of said group of springs, connections between said intermediate frame and certain of the border springs, and diagonally disposed stay wires 75 confined between the intermediate frame, and the upper frame and connected to opposite sides of the upper frame and to opposite sides of the intermediate frame.

3. In a spring structure, an upper frame, 80 a lower frame, border springs arranged between the upper and lower frames and having connection therewith, a group of upper and lower springs arranged between the frames and within said border springs, an 85 intermediate frame arranged between the upper and lower frames and within the border springs and connected to said group of springs, and stay wire connections confined between the upper frame and said intermediate frame and arranged in parallelism and extending downwardly in opposite directions from the upper frame and connected at opposite sides of the intermediate frame so as to prevent lateral thrusts of the intermediate frame.

4. In a spring structure, an upper frame, a lower frame, border springs arranged between the upper and lower frames, a group of upper and lower springs arranged between the frames and within said border springs, the upper springs of said group being of lighter gage wire than the lower set of springs and of lighter gage wire than the border springs, an intermediate frame 100 arranged between the upper and lower frames and surrounding and connected to said group of springs and confined within the border springs, link connections between said intermediate frame and some of the 105 border springs, and a stay wire connection between the upper frame and the intermediate frame, said stay wire having rigid connection with the upper frame and the intermediate frame.

5. In a spring structure, an upper frame, a lower frame, border springs arranged between the upper and lower frames, a group of upper and lower springs arranged between the frames and within said border 115 springs, the upper springs of said group being of lighter gage wire than the lower set of springs and of lighter gage wire than the border springs, an intermediate frame arranged between the upper and lower frames 120 and surrounding and connected to said group of springs and confined within the border springs, link connections between said intermediate frame and some of the border springs, and stay wires rigidly con- 125

nected to the upper frame and also rigidly connected to said intermediate frame and confined between the upper frame and the intermediate frame and arranged between 5 corresponding rows of springs.

6. In a spring structure, a frame, border springs connected to the frame, a group of upper and lower springs arranged within the border springs, a frame arranged within 10 the border springs and surrounding said group of springs and connected to the group of springs, a staying means between the upper frame and the intermediate frame, means connecting the lower convolutions of 15 the upper springs of said group of springs, and means connecting the upper convolutions of the lower set of springs of said group of springs.

7. In a spring structure, a frame, border springs connected to the frame, a group of 20 upper and lower springs arranged within the border springs, a frame arranged within the border springs and surrounding said group of springs and connected to the group of springs, a staying means between the 25 upper frame and the intermediate frame, means connecting the lower convolutions of the upper springs of said group of springs, means connecting the upper convolutions of the lower set of springs of said group of 30 springs, and connections between said intermediate frame and some of the border springs.

In testimony whereof I have hereunto set my hand.

DESIRE H. VAN HOVE.
